BY

Geo. P. Kimmel. ATTORNEY.

UNITED STATES PATENT OFFICE.

VICENTE M. ALCARAZ, OF SAN JUAN, PORTO RICO.

CLOSURE-MEMBER SECURING AND BOWING DEVICE.

Application filed May 14, 1926. Serial No. 109,133.

This invention relates to closure member securing and bowing devices and pertains particularly to a device for securing in open or closed position, shutters or casement windows.

The primary object of this invention is the provision, in a manner as hereinafter set forth, of a hinged closure member securing device which will hold a closure member in any one of a plurality of open positions, and which will also securely lock the closure member when in fully closed position.

Still another object of the invention is the provision, in a manner as hereinafter set forth, of an improved latching means for the brace rod of a hinged closure member, whereby the brace member which also serves as a holding bar, is prevented from being moved by any person, from the outside of the closure member.

A further and final object of the invention is the provision, in a manner as herein-after set forth, of a hinged closure member of simple, strong and durable design, positive and sure in its action, easily secured in position and comparatively inexpensive to manufacture.

The invention will be best understood from a consideration of the following detailed description taken in connection with the accompanying drawing forming a part of this specification, with the understanding that the invention is not confined to any strict conformity with the showing of the drawing but may be changed and modified so long as such changes and modifications mark no material departure from the salient features of the invention as expressed in the appended claim.

In the drawing:—

Figure 1 shows a horizontal section through a wall and window frame, showing a casement window hingedly secured in said frame and showing the device embodying this invention in position.

Figure 2 shows the device embodying this invention in elevation and a portion of the window casement to which it is attached.

Figure 3 shows in longitudinal section a keeper member used in connection with this device.

Figure 4 shows the keeper member in end elevation.

Figure 5 shows a top plan view of a latch bar forming a part of the keeper member and,

Figure 6 shows in side elevation, a supporting hook for a portion of the device.

Referring now to the drawing in detail wherein like numerals of reference indicate corresponding parts throughout the several views, the numeral 1 indicates a portion of a wall in which a window frame 2 is fitted, the frame consisting of the usual side members 3 and the sill 4. Hingedly secured in the frame to one of the side members 3 by means of the hinge structure 5, is a casement window indicated as a whole by the numeral 6.

The holding device embodying this invention is formed in two units, one of the units comprising a plate 7 adapted to be secured by means of the screws 8, to the lower portion of the sash 6, as shown in Figure 2 and adjacent the hinged side thereof. This plate 7 has a pair of spaced parallel arms 9 extending from the face thereof and at an angle with respect to the frame of the casement sash, and pivotally secured between these arms at the free outer ends thereof, by means of the pivot pin 10, is a securing arm or bar 11. This bar 11 as is shown, is of substantial length and has at its free end the transversely positioned head 12. The outer free end of the bar is thus T-shaped as shown in Figures 2 and 3. The head 12 of the bar 11, has a notch 13 formed therein adjacent one end and opposite the side in which the end of the bar 11 is secured.

Adapted to be secured to the lower rail of the casement sash 6, is a plate 14 having secured upon the face thereof a combined bar supporting hook and handle or finger grip member indicated as a whole by the numeral 15. This member as is clearly shown in Figure 6, constitutes a body portion 16 which is secured against the plate 14 and this body portion merges into an upwardly and outwardly curved portion which terminates in a vertical upper end 17 adapted to be used as a finger hold. The lower portion of the bar body 16 is curved and turned back upon itself as at 18, terminating in the free portion or hook bill 19 which is in spaced parallel relation with the body portion 16. As shown in Figure 2, when the holding member 15 is in position with

the window closed, the bar 11 rests in the loop or curved portion 18 of the hook and as this member is preferably fixed to the casement sash between the plate 7 and the far 5 side of the sash, it serves as an additional brace for the bar when the head 12 is fixed in the keeper member, which is to be described.

The other unit of the sash securing device comprises an elongated casing indicated as 10 a whole by the numeral 20. This casing 20 comprises a base plate 21 through which at the ends thereof there are formed apertures for the passage of securing screws 22. The casing is adapted to be secured to the 15 window sill 4 at the inner side thereof and adjacent the opposite side from that to which the casement sash 6 is hinged. The casing 20 is completely closed, the top thereof as indicated at 23, being removable. 20 This removable top is provided with a plurality of longitudinally extending apertures 24 into any one of which, the notched end 25 of the head 12 is adapted to be fixed to hold the casement sash in any desired adjusted position.

Within the casing 20 there is located a latch member indicated as a whole by the numeral 25. This latch member comprises an elongated plate portion 26 having each 30 end thereof upturned as indicated at 27 and 28. The plate 26 is of sufficient width to snugly fit in the casing 21 and is of such length as to bring the ends 27, when the upturned end 28 is positioned against one end 35 wall thereof, to a point slightly beyond the farthest aperture 24. This upturned portion 27 has an inwardly extending head 29 setting up an engaging hook adapted to engage in the notch 13 of the head 12 when 40 the same is projected through the end aperture 24 which is adjacent this head 29. The other upturned end 28 of the plate 26 has extending from the outer wall thereof the button 30 which is adapted to be positioned 45 in the aperture 31 formed through one end wall of the casing 20.

Positioned between the other end walls of the casing and the outer side of the upturned end 27 of the plate 26, is a spring 32 which 50 normally acts to hold the latch member in the position in which it is shown in Figure 3, that is with the button 30 projected as far through the aperture 31 as possible.

Extending transversely of the interior of 55 the casing 20 adjacent the wall 28 of the latch member 25, is a bar 33 and positioned between this bar 33 and the inner side of the upturned end 28, is a coiled spring 34 which acts in conjunction with the spring 60 32 to maintain the head or hook 28 of the latch in the position for engagement in the notch 13 of the head 12. It will be readily seen from the foregoing description that when the notched end of the head 12 is 65 forced through the aperture 24 in the cas-

ing 20, nearest the hooked head 29, that the latch will be forced toward one end of the casing against the tension of the springs 32 and 34 and when the notch is in the proper position, the head 29 of the latch will be forced forwardly by the compressed springs to engage in the notch. The bar will thus be securely held in connection with the casing 20. When it is desired to release the head 12 pressure is applied to the button 70 30 thus forcing the latch longitudinally of the casing to disengage the head 29 from the notch 13 whereupon the head is free to be removed. As will be readily observed this locking action only takes place when 75 the casement sash is in closed position and when the sash is to be held in partly open position by the device, the head is engaged in the other aperture, according to the distance the sash is open, and is not locked by 80 the latch structure 25.

Secured to that end wall of the casing 20 through which the button aperture 31 is formed, is a hinged closure member 35 which is hingedly connected as at 36 to the 90 wall of the casing. A spring 37 acts upon the door 35 to normally keep the same closed. Extending from the central portion of the cover or door 35 is a stud 38 by means of which the door can be raised to 95 enable one to press the button 30 for the release of the bar 11.

Secured to the sill 4 at an appropriate point between the casing 20 and that side of the window frame 3 to which the sash 6 is 100 hinged, is a block 39 having a pair of upwardly opening recesses 40 formed in the top thereof. These recesses extend through the block and are reduced at their inner ends for extension therethrough of securing screws 41 by means of which the block is secured to the sill 4. When the sash 6 is in fully open position as indicated in dotted lines in Figure 1 the brace or securing bar 11 has the lower end of the cross head 12 110 secured in one of the apertures 40 to maintain the sash in this open position, in the manner shown.

From the foregoing description it will be readily seen that the structure herein set 115 forth is of simple construction and at the same time will efficiently operate to securely lock the casement window or shutter to which it is applied, or hold the same in partially open position as desired.

Having thus described my invention what I claim is:—

A closure member bower and fastener, comprising a securing arm adapted to be secured at one end to a closure member, a 125 casing adapted to be secured adjacent said closure member and having a plurality of apertures formed through one wall thereof to receive the free end of said arm to hold the closure member in set position, a slid- 130

ing plate positioned in said casing having each end thereof upturned, one upturned end being formed to set up a hook, a button formed upon the outerside of the other upturned end and exposed through one end of said casing, and a spring element acting upon said plate to cause the hook thereof

to engage the free end of said arm when the same is projected through one of said apertures, said arm being disengaged by pressure on said button.

In testimony whereof, I affix my signature hereto.

VICENTE M. ALCARAZ.
